UNITED STATES PATENT OFFICE.

E. TOTMAN, OF COLUMBUS, PENNSYLVANIA.

IMPROVEMENT IN SAWING-MACHINES.

Specification forming part of Letters Patent No. 43,724, dated August 2, 1864.

To all whom it may concern:

Be it known that I, E. TOTMAN, of Columbus, in the county of Warren and State of Pennsylvania, have invented a new and Improved Sawing-Machine; and I do hereby declare that the following is a full, clear, and exact description thereof, which will enable those skilled in the art to make and use the same, reference being had to the accompanying drawings, making a part of this specification, in which—

Figure 1 is a side sectional view of my invention, taken in the line xx , Fig. 2, Fig. 2, a plan or top view of the same.

This invention relates to a new and improved machine for sawing logs and timber transversely, designed more especially for sawing logs into suitable lengths for fuel.

A represents what may be termed the "base" of the machine, constructed in any suitable manner, and having an upright, B, at one end of it, through which a vertical shaft, C, passes, the latter having a crank-wheel, D, on its lower end, to which a pitman, E, is attached, said pitman having a saw, F, secured to its outer end. The shaft C has a box, G, placed on its upper end above the upright B, the box being allowed to turn freely on the shaft, and on the top of the box G there is placed a shaft, H, having a bevel-wheel, I, upon it, the latter gearing into a bevel-pinion, J, on the shaft C. To the shaft H a shaft, K, is attached by a universal joint, a , having a wheel, L, on its outer end, the periphery of which is provided with spurs b , to prevent slipping. The outer end of the shaft H has its bearing in the cross-piece c of a frame, M, composed of said cross-piece, and two bars d , which are connected to opposite sides of the box G by a pivot-bolt,

e , to admit of said frame rising and falling. The horse is attached to the frame M, and the latter drawn around the shaft C as a center, the base A having a platform, N, upon it for the horse and wheel L to pass over. The shaft K is rotated by the wheel L and the bevel-wheel I, communicating motion to the shaft C through the medium of the bevel-pinion J and the crank-wheel D and pitman E, communicate a reciprocating movement to the saw F. The shaft K, it will be seen, is allowed to rise and fall with the frame M in consequence of being connected to the shaft H by the universal joint a . A circular track may be made for the wheel L to run upon, or the earth may simply be graded and pounded to form a hard surface.

Thus it will be seen that by a very simple mechanism I obtain an effective sawing-machine, which may be constructed at a small cost, equally so as those which are not provided with any means for applying a motor.

I claim as new and desire to secure by Letters Patent—

The frame M, attached to a box, G, on a vertical shaft, C, and provided with a shaft, K, having a wheel, L, upon it near one end, and connected at its opposite end by a universal joint, a , to a shaft, H, in connection with the bevel-gearing IJ, placed on the shafts H and C, the crank-wheel D on the lower end of shaft C, the pitman E, and saw F, all arranged to operate substantially as and for the purpose set forth.

E. TOTMAN.
